(57) **CLAIM**

The ornamental design for a backing plate for a hook, as shown and described.

DESCRIPTION

FIG. 1 is a front view in perspective of a backing plate for a hook of the present invention as illustrated as installed; FIG. 2 is a rear view in perspective of the backing plate for a hook;

FIG. 3 is a front view in perspective of the backing plate for a hook;

FIG. 4 is a side view of the backing plate for a hook;

FIG. 5 is a rear view of the backing plate for a hook;

FIG. 6 is a front view of the backing plate for a hook;

FIG. 7 is a top view of the backing plate for a hook; and,

FIG. 8 is a bottom view of the backing plate for a hook. The broken lines depict environmental subject matter only and form no part of the claimed design.
